UNITED STATES PATENT OFFICE

ALBERT E. EVANS, OF PITTSBURGH, PENNSYLVANIA, ASSIGNOR TO PITTSBURGH PLATE GLASS COMPANY, A CORPORATION OF PENNSYLVANIA

APPARATUS FOR APPLYING FELTS TO GLASS POLISHING BLOCKS

Application filed April 26, 1930. Serial No. 447,492.

The invention relates to apparatus for applying the felt sheets employed in the polishing of plate glass to the metal runner blocks. The sheet of felt is ordinarily square and is held in place on the annular block by means of a metal ring which encircles the periphery of the block and clamps the corner portions of the felt to such periphery. Heretofore, the operation of applying the felt has been done by hand, the spindle of the block being removed, the block turned upside down and laid on a table, the felt applied, and the clamping ring positioned on the felt and hammered down, so that it clamps the corners of the felt sheet between its inner surface and the periphery of the block. The object of the present invention is to provide a simple, convenient apparatus, which can be employed to apply the felt without removing the spindle and with a minimum of labor, and which will apply the felt more accurately and smoothly than is ordinarily done by the hand operation. One embodiment of the invention is illustrated in the accompanying drawings, wherein:

Figure 1 is a vertical section through the apparatus with the runner block carried thereby in position to receive its polishing felt. Fig. 2 is a side elevation of the apparatus. Fig. 3 is a partial plan view and partial section on the line III—III of Fig. 1. Fig. 4 is a section on the line IV—IV of Fig. 3.

Referring to the drawings, 1 is a metal polishing block in the form of a disc provided with a spindle 2, to which the felt sheet 3 of rectangular cross section is to be applied. The runner block is brought to the position shown by means of the lifting tongs 4 whose ends are formed to engage the groove 5 at the upper end of the spindle, the tongs being held in closed position by means of the clamping ring 6 and being supported and moved about by means of a crane which is not shown.

The framework of the apparatus comprises a base plate 7 to which is secured a casting 7a, a pair of channels 8, 8 bolted to the casting 7a, and a cross head 9 secured by bolts or other suitable means to the upper ends of the channels. The cross head is provided with an annular recess 10 for receiving the

spindle 2 of the runner block, such recess being open on one side, as indicated in Fig. 3 to permit the spindle to be moved to the position shown in Fig. 1. The recess 10 is provided with the three bushings 11, 12 and 13, 55 the bushing 12 being mounted for movement of rotation and being provided with a handle 14 (Fig. 3). After the spindle has been positioned in the bushings 11, 12 and 13, it is locked in such position by the bushing 12 60 which is rotated through an angle of about 90 degrees to close the open side of the recess 10.

Mounted for vertical movement below the cross head 9 is a carrier 15 having a plunger 65 portion 16 fitting into a cylinder 17 which is part of the casting 7a bolted to the base 7. The carrier is also guided in its movements by means of a pair of rods 17a which are screwed into the carrier and extend through 70 guide holes in the cylinder casting. Fluid pressure is admitted to the cylinder below the end of the plunger 16 in order to move the carrier upward and perform the pressing operation, as later described. Secured in the 75 lower end of the plunger centrally thereof is a post 18, upon which a sleeve 19 is mounted for relative vertical movement. The post is slotted, as indicated at 20, and a bolt 21 carried by the lower end of the sleeve extends 80 through this slot. A spring 22 is located in the sleeve intermediate the upper end of the post 18 and the cap 23 which is screwed into the upper end of the sleeve.

The carrier 15 is provided with an annular 85 shoulder 24 which carries the felt clamping ring 25. The upper edge of the carrier is provided with four projecting corners 26 (Fig. 3) and at the edge of each of these corners is a pair of plates 27, 27 bolted in position and projecting slightly above the upper edge of the carrier, as indicated in Fig. 2. These corner members constitute a centering means for the felt 3 so that when the felt is laid on the top of the carrier with its corners fitting between the plates 27, 27 it is centered with respect to the carrier and also with respect to the runner block 1, to which the felt is to be applied. The felt is thus supported at its corner portions by the carrier 95 100

and at its central portion by the cap 23 which is yieldingly supported by the spring 22 in the position shown in Fig. 1. The inner surface of the carrier just above the shoulder 24 which carries the ring 25 is preferably inclined, as indicated at 28, to assist in centering the ring 25 when it is dropped into position and to provide clearance for the felt at its corner portions when the carrier is moved up to press the ring 25 over the felt.

In operation, the runner block 1 is positioned, as indicated in Fig. 1 with its upper surface against the lower end of the cross head 9, a felt sheet and the clamping ring are applied to the carrier 15 and fluid pressure is admitted to the lower end of the plunger 16 to cause the carrier to move upward. The upward movement of the carrier moves the felt up against the bottom surface of the runner block and a further movement of the carrier, the ring 25 is carried upward pressing the corners of the felt sheet up alongside the periphery of the block 1, this movement being continued until the ring engages the shoulder 29 on the runner block. During this clamping operation, the cap 23 holds the center of the felt sheet against the lower side of the runner block, the spring 22 serving to permit the periphery of the carrier to move up to perform its clamping function after the cap 23 has been stopped in its upward movement. The carrier is now moved down to starting position, thus completing the cycle. The device is easily operated and applies the felt accurately and smoothly without the necessity of removing the spindle 2 from the block as has heretofore been customary. As shown and described, the cross head 9 is fixed and the carrier 15 is movable, but it will be understood that the invention contemplates a reversal as to this condition as the carrier may be fixed and the cross head movable, all that is necessary being an arrangement to provide for a movement of approach between the two members. The advantages of the construction will be readily apparent to those skilled in the art.

What I claim is:

1. In combination in apparatus for applying a felt sheet to a runner block having a spindle, a cross head having a supporting surface facing downwardly so as to engage the upper surface of a runner block and having a central recess opening laterally for receiving the spindle of the runner block, means for engaging the upper end of the spindle and supporting the block so that its spindle lies in said recess and the face of the block is held against said supporting surface, a carrier below the cross head centered with respect thereto, means on the carrier for supporting a felt sheet to be applied to said block, other means on the carrier below the first means for supporting a clamping ring and means for causing a movement of ap-

proach of the carrier with respect to the cross head to cause the felt sheet to engage the lower face of the block and to cause the clamping ring to move over the felt sheet into position surrounding the block.

2. In combination in apparatus for applying a felt sheet to a runner block having a spindle, a cross head having a supporting surface facing downwardly so as to engage the upper surface of a runner block and having a central recess opening laterally for receiving the spindle of the runner block, means for engaging the upper end of the spindle and supporting the block so that its spindle lies in said recess and the face of the block is held against said supporting surface, a carrier below the cross head centered with respect thereto, means on the carrier for supporting at its edges a felt sheet to be applied to said block, other means which are spring pressed mounted on the carrier for supporting the sheet at its center, means on the carrier below the sheet supporting means for supporting a clamping ring, and means for causing a movement of approach of the carrier with respect to the cross head to cause the felt sheet to engage the lower face of the block and to cause the clamping ring to move over the felt sheet into position surrounding the block.

3. In combination in apparatus for applying a square felt sheet to a runner block, a cross head having a supporting surface facing downwardly, means for centering the runner block beneath said surface with its upper face in opposition to said surface, a carrier below said cross head centered with respect thereto and having an annular flange provided with corner recesses for receiving the corners of the felt sheet to center it with respect to the carrier and said block, a shoulder lying inside said flange below the upper edge thereof and adapted to support a ring for clamping the felt sheet, and means for causing a movement of approach of the carrier with respect to the cross head to cause the felt sheet to engage the lower face of the block and to cause the clamping ring to move over the felt sheet into position surrounding the block.

4. In combination in apparatus for applying a square felt sheet to a runner block, a cross head having a supporting surface facing downwardly, means for centering the runner block beneath said surface with its upper face in opposition to said surface, a carrier below said cross head centered with respect thereto and having an annular flange provided with corner recesses for receiving the corners of the felt sheet to center it with respect to the carrier and said block, other means which are spring pressed on the carrier for supporting the felt sheet at its center, a shoulder lying inside said flange below the upper edge thereof and adapted to support a

ring for clamping the felt sheet, and means for causing a movement of approach of the carrier with respect to the cross head to cause the felt sheet to engage the lower face of the block and to cause the clamping ring to move over the felt sheet into position surrounding the block.

5. In combination in apparatus for applying a square felt sheet to a runner block, a cross head having a supporting surface facing downwardly, means for centering the runner block beneath said surface with its upper face in opposition to said surface, a carrier below said cross head centered with respect thereto and having an annular flange provided with corner recesses for receiving the corners of the felt sheet to center it with respect to the carrier and said block, said flange having its inner wall tapering inwardly from its upper edge down, a shoulder carried by the flange below said tapered wall, and adapted to support a ring for clamping the felt sheet, and means for causing a movement of approach of the carrier with respect to the cross head to cause the felt sheet to engage the lower face of the block and to cause the clamping ring to move over the felt sheet into position surrounding the block.

6. In combination in apparatus for applying a felt sheet to a runner block having a spindle, a cross head having a supporting surface facing downwardly so as to engage the upper surface of a runner block and having a central recess opening laterally for receiving the spindle of the runner block, means for engaging the upper end of the spindle and supporting the block so that its spindle lies in said recess and the face of the block is held against said supporting surface, a support below the cross head for the felt sheet and for a clamping ring centered with respect to the cross head, and power means for causing a movement of approach of the support with respect to the cross head.

7. In combination in apparatus for applying a felt sheet to a runner block having a spindle, a cross head having a supporting surface facing downwardly so as to engage the upper surface of a runner block and having a central recess opening laterally for receiving the spindle of the runner block, means for engaging the upper end of the spindle and supporting the block so that its spindle lies in said recess and the face of the block is held against said supporting surface, means for pressing the spindle into said recess, a support below the cross head for the felt sheet and for a clamping ring centered with respect to the cross head, and power means for causing a movement of approach of the support with respect to the cross head.

In testimony whereof, I have hereunto subscribed my name this 12th day of March, 1930.

ALBERT E. EVANS.
